UNITED STATES PATENT OFFICE.

JAMES W. VAN CLEAVE, OF ST. LOUIS, MISSOURI, ASSIGNOR TO THE BUCK'S STOVE AND RANGE COMPANY, OF SAME PLACE.

DESIGN FOR A STOVE.

SPECIFICATION forming part of Design No. 27,357, dated July 13, 1897.

Application filed June 3, 1897. Serial No. 639,347. Term of patent 14 years.

To all whom it may concern:

Be it known that I, JAMES W. VAN CLEAVE, a citizen of the United States, residing at the city of St. Louis, State of Missouri, have made 5 a new and original Design for Stoves, of which the following is a full, clear, and exact description, reference being had to the accompanying drawing, forming part of this specification, wherein the figure represents a perspective view of a stove embodying my new and original design.

This invention relates to a new and original design for stoves; and it consists in the shape and ornamentation of the same, all as will 15 hereinafter be described, and afterward pointed out in the claim.

The essential features of this design reside in the scroll ornamentation of the top, bottom, side, and end walls of the stove, which 20 scrolls, at certain points of meeting of said parts, are matched, as will hereinafter appear.

The stove as an entirety is oblong in shape. In the drawing, A indicates the legs, which 25 are ornamented with scrolls at their upper ends, as shown.

B indicates the bottom of the stove, whose side edges are ornamented with a line of scrolls.

C indicates the side panel, the entire surface of which is ornamented with scrolls of varying sizes.

D indicates the front wall of the stove, which is ornamented with scrolls. This front wall has a door D' similarly ornamented.

E indicates the back wall, which is also ornamented.

The scrolls at the meeting edges of the front and back walls and the side panels are matched, as shown, to make an integral de- 40 sign.

F indicates the top wall, which is ornamented with scrolls. This top wall has also ornamented lids F'.

What I claim is—

The design for a stove, substantially as herein shown and described.

In testimony whereof I hereunto affix my signature, in presence of two witnesses, this 29th day of May, 1897.

JAMES W. VAN CLEAVE.
